UNITED STATES PATENT OFFICE

161,891

COMBINED MICROPHONE AND SUPPORT UNIT

Vernon Karl Albert, Alhambra, Calif., assignor to
Altec Lansing Corporation, Los Angeles, Calif.,
a corporation of Delaware

Application June 19, 1950, Serial No. 10,622

Term of patent 14 years

(Cl. D26—14)

To all whom it may concern:

Be it known that I, Vernon Karl Albert, a citizen of the United States, residing at Alhambra, in the county of Los Angeles, State of California, have invented a new, original, and ornamental Design for a Combined Microphone and Support Unit, of which the following is a specification, reference being had to the accompanying drawing, forming part thereof.

The figure is a perspective of a combined microphone and support unit showing my new design.

I claim:

The ornamental design for a combined microphone and support unit, as shown.

VERNON KARL ALBERT.
